UNITED STATES PATENT OFFICE.

IVAN D. THORNBURGH, OF BERKELEY, CALIFORNIA, ASSIGNOR TO AMERICAN CAN COMPANY, OF SAN FRANCISCO, CALIFORNIA, A CORPORATION OF NEW JERSEY.

METHOD OF AND APPARATUS FOR GASKET LINING CAN ENDS.

Application filed April 24, 1919. Serial No. 292,416.

To all whom it may concern:

Be it known that I, IVAN D. THORNBURGH, a citizen of the United States, residing at Berkeley, in the county of Alameda and State of California, have invented certain new and useful Improvements in Methods of and Apparatus for Gasket Lining Can Ends, of which the following is a specification.

10 The hereinafter described invention relates to a method and apparatus for the paper gasket lining of can ends for subsequent use in connection with the hermetic sealing of containers for the preservation of food products.

15 The method at present employed for paper gasket lining can ends, and as well known, comprises the cutting of a gasket ring liner or a liner of proper shape either from a web, sheet or disk of liner material, which as cut or formed therefrom is either directly applied onto the flange of a can end or applied thereto at a subsequent period, but before the can end is utilized for 20 application and seaming to the container for the food product. This method of gasket lining of the can ends is objectionable due to the heavy loss occasioned by reason of the wastage of paper resulting therefrom, and 25 further objectionable by reason of the expense required to properly maintain the cutting mechanism in condition for efficient work.

30 The present method invention resides in applying powdered paper stock onto the flange surface of a can end previously treated with a coating of a suitable sizing material and which sizing material in the present case preferably consists of gelatine, due 35 to the fact that it is non-injurious, tasteless and does not in any manner affect the contents of the container after the hermetic sealing thereof. After the sizing of the flange of the can end to be gasket lined, the 40 said can end flange is then presented to a flowing stream of the powdered paper stock, the quantity thereof applied to the sized flange of the can end being such as to 45 thoroughly cover the sized surface thereof, the sizing serving to cause the powdered paper stock to adhere to the surface of the 50 can end flange.

55 After the application of the powdered paper stock to the sized surface of the can end, the said end is then transferred from the

sizing and powdered paper stock applying station to a position where the coated can end is subjected to the application of heat for the drying of the sizing solution or compound applied to the flange of the can end. 60 By this method there is built up, so to speak, on the flange of the can end a gasket liner composed of or formed from powdered paper stock.

65 While in the carrying out of my invention preference is given to the use of paper stock as the powdered material to be used in the formation of the gasket liner, it will be understood that any other suitable form of powdered fiber or cellular material may 70 be employed in place thereof for the building up of the gasket liner, just so long as the fiber material is of such a character as to be harmless relative to the contents of the container for which the can end is to 75 be utilized for the hermetic sealing thereof, and therefore, generically, the invention contemplates the utilization of any form of powdered fiber or cellular material capable of being used for the successful carrying 80 out of the invention.

85 The preferred embodiment of a practical apparatus for the carrying out of the invention comprises interconnected cooperating working instrumentalities for delivering 90 and receiving an unlined flanged can end and positioning the same in axial alignment with means for applying as by a jet stream to the surface of the flange thereof a suitable stream of sizing material and during the application of which to the surface of the can end flange the said can end is revolved, and as sized placing the surface thereof in line to receive thereon a jet stream of powdered fibrous or cellular material for 95 the forming or building up of the gasket liner; thence transferring the can end with its built-up liner to means for applying heated air to the surface of the lined can end for the drying of the applied sizing material.

100 Referring to the accompanying sheets of drawings wherein is illustrated a simple, practical and efficient apparatus for the carrying out of the method invention,

105 Fig. 1 is a plan view of the apparatus, illustrating the can end feed mechanism, the means for delivering the powdered material onto the flange of the can end, the means for heating and drying of the can end, and the 110

mechanism for imparting timed operation to the respective working parts of the apparatus.

Fig. 2 is a vertical sectional view taken on the line 2—2 Fig. 1 of the drawings and viewed in the direction of the arrows, illustrating more particularly the means for the feeding of flanged can ends from a stack of ends contained within a magazine or holder, 10 the drying means for the gasket lined ends and further illustrating the means for actuating the working parts of the apparatus in timed relation.

Fig. 3 is a sectional view taken on the line 15 3—3 Fig. 1 of the drawings and viewed in the direction of the arrow, said view illustrating the mechanism for imparting intermittent movement to the rotatable turret which receives and conveys the unlined can 20 ends from the can end feed station to the lining station of the apparatus.

Fig. 4 is a broken plan sectional view taken on the irregular line 4—4, Fig. 3 of the drawings and viewed in the direction of the arrows, said view illustrating the mechanism controlling the feed of the can ends to be lined from the stack of can ends and further illustrating the plunger actuated 25 means controlling the discharge of the powdered material for application to the sized surface of the flanged can end.

Fig. 5 is a sectional side elevation taken on the line 5—5 Fig. 3 of the drawings and viewed in the direction of the arrows, said view disclosing the Geneva actuated mechanism for imparting intermittent rotation to the can end transfer turret.

Fig. 6 is a broken detailed sectional view 40 in elevation, taken on the line 6—6 Fig. 1 of the drawings and viewed in the direction of the arrows.

Fig. 7 is a broken detailed sectional view 45 taken on the irregular line 7—7, Fig. 6 of the drawings and viewed in the direction of the arrows, said view disclosing the vessel for holding the sizing liquid, and the mechanism for controlling the discharge thereof from within the said vessel.

Fig. 8 is a fragmental sectional view taken 50 on the line 8—8, Fig. 6 of the drawings and viewed in the direction of the arrows.

Referring to Figs. 1, 2 and 3 of the drawings the reference numeral 1 is used to designate any suitable form of a frame structure 55 capable of sustaining the working parts of the apparatus and which said structure is provided with a horizontally disposed table 2. Within suitable bearings of the said frame structure is mounted for rotation a transversely disposed drive shaft 3, to one 60 end of which is secured a belt pulley 4 for receiving power from any suitable source of power not shown herein. To the shaft 3 and within the frame structure 1 is secured a drive gear 5, which is in mesh with a gear 6

secured to the lower extremity of a vertically disposed shaft 7, which shaft is extended above the table 2 and works in bearings 8 and 9, the latter of which is carried by the yoke plate 10 secured to the table 2 of 70 the frame structure in any suitable manner.

Over the surface of the table 2 works a horizontally disposed rotatable turret 11, having a can end feed station A, a liner or gasket applying station B, a drying station 75 C and a discharge station D, which turret is secured by bolts 12 to a hub 13 loosely surrounding the shaft 7 and formed at its lower end into a gear 14, which meshes with a gear 15 secured to a short horizontally disposed shaft 16, working within bearings 16' of the frame structure 1. To the outer end of the said shaft 16 is secured a Geneva wheel 17, which is driven by means of the Geneva arm 18 secured to the drive shaft 3, Figs. 3 80 and 5 of the drawings, so that the rotary motion of the shaft 3 is transmitted to the shaft 16 through the medium of the said Geneva wheel 17 and its actuating arm 18, for imparting an intermittent rotation to the horizontally disposed turret 11. The said turret 11 is provided with a series of spaced circumferentially disposed vertical pockets 19, which are arrested at the said stations in 85 turn, and are adapted to receive successively 90 therein flanged can ends to be lined as the said pockets or apertures 19 of the turret 11 are brought successively into vertical alignment with the holder or magazine 20 at the station A, which is adapted to contain a stack 95 of flanged can ends 21. The lowermost end of the stack within the holder 20 rests upon and is supported by the feed rods 22, which 100 extend through the bottom of the holder 20 and each of which is provided with a notched 105 section 23, which is adapted to engage and receive a portion of the flange of the lowermost can end. These feed rods 22 have continuous rotation imparted thereto by means 110 of the train of gears 24, Figs. 1 and 4 of the drawings. On the shaft 25 for the innermost gear of the train of gears there is secured a spiral gear 26, which meshes with a gear 27 115 secured to the central shaft 7 above the horizontally disposed rotatable turret 11 and which transmits the continuous rotation of the said shaft 7 to the can end feed rods 22. As these rods are turned or rotate within 120 bearings of the can end holder 20, the notched sections 23 thereof engage a portion of the flange of the lowermost end and causes a lowering thereof from the stack of ends contained within the holder 7 until the said lowermost can end is moved from within the 125 said holder, at which time the cut-out lowermost can end of the stack is deposited within one of the pockets or apertures 19 of the rotatable turret 11 at such time positioned in axial alignment with the can end holder, 130 it being apparent that after the notched sec-

tions 23 of the feed rods 22 are turned downwardly for the lowering or cutting out of the lowermost end of the stack of ends, that the remainder of the stack is supported and upheld by the said feed rods 22.

The moment a cut-out can end is deposited within one of the pockets or apertures 19 of the turret 11, a step rotation or movement is imparted to the said turret to convey the 10 cut-out can end from the can end feed station to the lining mechanism of the apparatus.

When the can end is transferred for positioning in axial alignment with the lining mechanism, the same is received onto the 15 surface of a rotatable can end holder 28, Figs. 3 and 6 of the drawings. This holder or support 28 at the station B is provided with a depending stem 29 which works within a suitable bearing 30 and at its lower 20 end has secured thereto a gear 31, which meshes with a gear 32, secured to the drive shaft 3. When the unlined can end stands in this position, one portion of its 25 flange is immediately below and in axial alignment with a jet nozzle 33, Fig. 6 of the drawings. With the said jet nozzle connects one end of an air supply pipe 34 which admits air under pressure into the valve chamber 35 of the said nozzle 33, the air 30 admitted into the said chamber escaping therefrom through the central discharge passage 35' of the nozzle 33, and with which passage connects one end of a syphon tube 36; the opposite end of the said syphon tube 35 extending downwardly within a liquid holding vessel 37 secured to and supported by the yoke 10, Figs. 3, 7 and 8 of the drawings, which said vessel is adapted to hold a body of sizing liquid 38, preferably 40 formed of gelatine and into which body of sizing liquid the lower end of the syphon 36 extends. Through the upper portion of the nozzle 33 and adapted to open and close communication between the valve or 45 pressure chamber 35 and the vertical passage 35' of the nozzle 33 is fitted a vertically movable valve 39, which at its upper end is pivotally connected to a lever 40, which is fulcrumed to a bracket 40', depending from the yoke 10, Figs. 1 and 7 of the drawings. The fulcrumed lever 40 at its outer end carries a follower roll 41 which works within a cam groove 42, formed in the cam 43 secured to the continuously driven central 50 shaft 7, Figs. 2 and 3 of the drawings. When the valve 39 is in raised position to establish communication between the valve or pressure chamber 35 and the vertical passage 35' of the nozzle 33, air under pressure supplied from the pipe 34 discharges from the nozzle 33 and the suction created by the flowing air under pressure causes a 55 syphoning of the sizing liquid 38 from within the vessel 37 and the discharge thereof as a jet stream onto the surface of the flange

of the rotating can end 21, resting at such time upon the rotatable support 28, so that the entire circumference of the flange of the can end is sized with the liquid ejected under pressure from the jet nozzle 33. By 70 the time the entire circumference of the surface of the flange of the can end has been coated with the sizing liquid, the action of the cam 43 is such as to throw the fulcrumed lever 40 to lower the valve 39 75 to close the valve or pressure chamber 35 against the escape of air therefrom through the jet nozzle 33, and by so doing breaking the syphoning of the sizing liquid. To the vessel 37 is also secured a jet nozzle 44, 80 (Fig. 8), which is provided with a lateral extension 44' having a passageway 45 therein which communicates with the central bore 45' of the nozzle 44. This nozzle 44, like the nozzle 33 is provided with a valve pressure chamber 46 to which is connected one end of an air supply pipe 46', which pipe 46' communicates with an air pressure supply pipe 47 which leads from a suitable source of air under pressure and with the 85 said air supply pipe 47 also connects the air supply pipe 34 for admitting air under pressure into the valve chamber of the nozzle 33. The discharge of air under pressure from within the valve chamber 46 of the nozzle 44 is controlled by means of a vertically movable valve 48, similar in construction to the valve 39 of the nozzle 33, the upper end of the said valve 48 being pivotally connected to a lever 49, which is fulcrumed to a bracket 49' depending from the yoke 10. The said fulcrumed lever 49 at its inner end carries a follower roll 50, which works within a cam groove 50' of the cam 43. 90 To the lateral extension 44' of the nozzle 44 is connected the lower discharge end 51 of a container 52, which is adapted to hold a body of powdered or pulverulent liner material 53, the said container 52 being secured to the yoke 10 by means of brackets 52', Figs. 1 and 3 of the drawings. Within the extension 44' of the nozzle 44 works a reciprocating plunger 54 having a stem pivotally connected to a link 54' which link is connected to a crank 55 secured to the lower end of a vertically disposed shaft 55', Figs. 3, 4 and 6 of the drawings. To the upper end of the vertical shaft 55' working in bearings 56, there is secured a crank arm 56' pivotally 100 connected to the outer end of the stem 57 of a yoke 57' straddling the central shaft 7. The said yoke 57' carries a follower roll 58, which is adapted to work within the lower cam groove 58' of the cam 43. The powdered or pulverulent material held within the container 52 feeds into the passage-way 45 of the lateral extension 44' of the nozzle 44 and as the plunger 54 is thrown inwardly 105 by the action of the described connection be-

tween the cam 43, the body of powdered material resting within the passage-way 45 is moved forwardly and into the air stream flowing under pressure through the bore 45' of the nozzle 44 and is ejected thereby from the nozzle as a powdered jet stream under pressure onto the sized surface of the can end flange. It will be understood that as the valve 48 is raised to establish communication between the valve or pressure chamber 46 and the bore 45' of the nozzle 44, that the plunger 54 will have moved inwardly such a distance as to close communication between the container 52 and the passage-way 45 of the lateral extension 44'. The valve 48 is held in its raised or open position until the powdered material has been ejected over the entire sized surface of the can end flange, at which time the throw of the lever 49 is such as to lower the valve 48 to close the escape of air under pressure from within the valve chamber 46, and the throw of the connecting mechanism for the plunger 54 at such time is such as to move outwardly the plunger 54 to uncover the communication between the container 52 and the passage-way 45, so as to allow a flow of material from within the said container into the said passage-way for the supply of a sufficient quantity of powdered material to serve as a coating for the next sized can end. It will be understood that the action of the levers 40, 49 and the yoke 57' is such as to cause the parts controlled thereby to move in timed relation, it being understood that the discharge of a jet stream of powdered material is cut off or maintained closed while the valve 39 of the nozzle 33 is opened for the discharge of a jet stream of sizing liquid onto the surface of the flange of the can end, and that when said valve 39 is moved to cut off or close the discharge of a jet stream of sizing material the valve 48 is opened for the discharge of a jet stream of powdered material onto the sized surface of the flanged can end, although, it will be understood that such is not absolutely necessary inasmuch as the valve controlling the discharge of the powdered material may be so moved as to open the nozzle 44 by the time a sized portion of the revolving can end is moved beneath the same.

After powdered material has been applied to the sized surface of the flange of the can end, a step movement is imparted to the horizontally rotatable turret 11 so as to convey the gasket lined can end to the heating means of the apparatus at the station C, said means in the present case comprises a hood 59, Figs. 1 and 2 of the drawings, beneath which hood the can end is brought to a state of rest. Heated air is supplied to within the said hood by means of the supply pipe 59', the heated air exhausting from within the said hood through the outlet con-

nection 60. The heat thus applied to the can end while resting within the hood 59 being for the purpose of drying the sizing solution which was deposited onto the flange of the can end prior to the application thereto of the powdered material for the building up of the gasket liner. It will be understood that as a lined can end is transferred to the drying means, that a can end to be lined is conveyed from the can end feed mechanism to the means for applying the sizing solution and the powdered material onto the surface of its flange for the forming of a gasket liner thereon. On the next step movement of the turret 11 the dried can end is moved to the opening 61 formed in the table 2, at the station D through which the lined can end falls into a discharge chute 62.

It is apparent from the foregoing that the width of the liner is dependent on the area of the surface of the can end flange covered by the sizing solution applied thereto, inasmuch as the powdered material will only adhere to the surface covered by said sizing solution, and equally so the depth or thickness of the gasket liner may be controlled by the number of rotations permitted the can end to be gasket lined while positioned beneath the nozzles for applying the sizing solution and powdered material to the flange thereof. In this manner gasket liners of any desired width and depth may be built up relative to the flange of the can end to be lined.

As stated, any suitable form of an adherent may be utilized as the sizing solution, in fact a fine mist spray of water may be employed for such purpose. Where a mist spray of water is utilized, the powdered paper or fibre when deposited thereon will absorb the moisture and form so to speak a pulp liner on the flange of the can end, which when dried to expel moisture therefrom will leave a finished paper gasket liner applied to the flange of the can end.

By the use of the described apparatus, it will be noted that a can end is received into one of the pockets of the rotatable turret 11 at the can end feed station A and is transferred by the said turret to the liner applying station B, and transferred from said station to the drying station C, and from the drying station C to the discharge station D, Figs. 1 and 4 of the drawings.

The intermittently operated mechanism of the apparatus is so timed with respect to the continuous working mechanism of the apparatus as to cause the same to operate in timed relation.

While the apparatus for the carrying out of the method invention has been described in its preferred embodiment of working parts, I do not wish to be understood as confining or limiting myself to the detailed

construction thereof, as I am fully aware that the same may be modified, varied and changed without creating a departure from the nature and scope of the invention.

5 Having thus described my invention what I claim as new and desire to protect by Letters Patent is:

1. The method of building up a gasket liner relative to a flanged can end for use 10 in the hermetic sealing of containers for food products, which comprises applying an innocuous sizing liquid to the surface of the flange of the can end to be lined, thence covering the said sized surface with a 15 powdered fiber lining material, rotating the can end on its axis during the applying of the liquid and then during the applying of said powdered material, and finally subjecting the can end so lined to the application 20 of heat for the drying of the sizing liquid to leave deposited on the flange of the said end a built-up gasket liner.

2. The method of gasket lining flanged can ends for use in the hermetic sealing of 25 food containers, which consists in first sizing the surface of the flange of the can end to be lined, applying to the sized surface a coating of powdered fiber lining material, rotating the can end on its own axis during 30 the sizing operation and then during the application of the powdered material, and thence drying the applied sizing liquid for leaving deposited on the flange of the can end a finished gasket liner.

3. The method of gasket lining flanged can ends which consists in conveying a flanged can end to a lining station, thence applying a sizing liquid to the surface of the flange of the can end, thence covering the sized surface with a powder of fiber lining material, rotating the can end on its axis during the sizing operation and then during the application of the powdered material, thence transferring the can end to a 45 heating station for the drying of the sizing liquid to leave deposited on the flange of the can end a built-up gasket liner.

4. The method of gasket lining can ends for use in the hermetic sealing of food containers, which comprises sizing the surface 50 of the flange of said can end, applying to the sized surface only a powder composed of paper stock and thence drying the applied sizing liquid for leaving deposited on the flange of a can end a built-up gasket liner.

5. The method of gasket lining flanged can ends, which consists in receiving a flanged can end at a can end feeding station, transferring the same to a lining station, 60 thence applying a sizing liquid to the surface of the flange of said can end, covering the sized surface with a coating of powdered paper stock, rotating the can end on its axis during the application of said liquid and 65 then during the application of said powdered

stock, and thence transferring the coated can end to a heating station for the drying of the sizing liquid to leave deposited on the flange of the can end a built-up gasket liner.

6. The method of paper gasket lining 70 flanged can ends, which consists in forming on the flange thereof a green liner by first coating the surface of the flange with a sizing liquid, thence building up thereon powdered paper fiber, rotating the can end 75 on its axis during said coating operation and also during said building-up operation, and thence drying the applied sizing liquid for the production on the flange of the can end of a finished paper gasket liner.

7. An apparatus for the gasket lining of flanged can ends, the same comprising a reservoir adapted to contain a liquid sizing solution, a holder adapted to contain a body of powdered fiber liner material, valved actuated means controlling the discharge of sizing liquid from the reservoir therefor and powdered liner material from the holder therefor, means for positioning a can end with its flange in alignment with said valved actuated means, mechanism for actuating said means respectively to apply to the surface of a can end flange sizing liquid and for covering the sized surface with the powdered fiber liner material and cutting off the supply thereof at predetermined times, and means for applying heat to the can end for drying the sizing liquid applied thereto to leave deposited on the flange thereof a built up gasket liner.

8. An apparatus for the described purpose, the same comprising an apertured rotatable member, can end feed mechanism for supplying successively to the apertures of said member flanged can ends to be lined, means for imparting rotation to said member for transferring flanged can ends from the feed station to a lining station and from the lining station to a heating station, valved actuated mechanism situated at the lining station for applying to the flange of the can end a coating of sizing liquid and covering the same by a powder of lining material, and means at the heating station for drying the sizing liquid to leave deposited on the flange of the can end a built-up gasket liner.

9. An apparatus for the described purpose, the combination with lining means comprising automatically actuated devices for applying a sizing liquid to the flange of a can end to be lined, and for applying a coating of powdered liner material to said surface of the can end, and means for actuating said devices for controlling the supply of the sizing liquid and of the powdered liner material to the flange of the can end, and means for rotating the can end on its axis in cooperation with said liquid applying means and said powder applying means.

10. In an apparatus for the described pur-

pose, the combination with valve actuated means for regulating the supply of a sizing liquid to the flange of a can end, valve actuated devices for regulating and controlling 5 the supply of powdered liner material to the sized surface of a can end, and air pressure supply means for ejecting the sizing liquid onto the flange of a positioned can end and for ejecting a jet of the powdered liner ma- 10 terial onto the sized surface of the said can end.

11. In an apparatus for the described purpose, the combination with a valve controlled nozzle for directing sizing liquid onto the 15 flange of a can end, a valve controlled nozzle for directing a stream of powdered liner material onto the sized surface of the said can end, means for controlling the supply of the powdered material to the said last men- 20 tioned nozzle, air pressure means associated with each of said nozzles for ejecting therefrom respectively a jet of sizing liquid and a jet of powdered liner material onto the flange of a can end, and devices controlling 25 the action of the valves of said nozzles for regulating the flow of air under pressure therethrough.

12. In an apparatus for the described purpose the same comprising a horizontally ro- 30 tatable turret provided with a series of circumferentially disposed vertical apertures for the reception of can ends, means for feeding successively to said apertures flanged can ends, mechanism for imparting inter- 35 mittent rotation to said turret for transferring the flanged can ends from the can end feed mechanism to a lining station of said apparatus, a rotatable support situated at the lining station for receiving thereon a can 40 end delivered thereto, means situated at said station for applying to the flange of a re- volving can end delivered thereto a coating 45 of sizing liquid, and further means situated at said station for applying to the sized sur- face of the can end a coating of powdered 50 fiber material, and devices for actuating said means respectively and successively for controlling the supply of the sizing liquid and the supply of the powdered liner material onto the flange of a positioned can end.

13. The method of building up a gasket liner on the flange of a can end, which comprises rotating the can end on its axis and successively applying to the flange thereof while so rotated, first an innocuous adhesive 55 material and then a finely divided gasket material, the latter being applied at a defined point opposite to and on said adhesive material.

14. The method of building up a gasket 60 liner on the flange of a can end, which comprises rotating the can end on its axis and in a horizontal plane, and successively applying to the flange thereof an innocuous adhesive and then delivering a powdered paper stock 65 at a definite point opposite to and on said adhesive material while the can end is so rotated.

15. The method of building up a gasket liner on the flange of a can end, which comprises rotating the can end on its own axis 70 and successively applying to the flange only thereof while so rotated an adhesive and on the adhesive a soft compressible vegetable substance in finely divided condition. 75

16. The method of building up a gasket liner on the flange of a can end, which comprises holding the can end in a defined position and rotating the same, and successively applying to the flange only thereof while so held and rotated, an adhesive and on the adhesive a finely divided gasket material. 80

17. The method of building up a gasket liner on the flange of a can end, which comprises holding the can end at an applying 85 station and applying to the flange only thereof an adhesive, and at the same station and while the can end is so held applying to the adhesive a powdered gasket material, the said applications of both the adhesive 90 and gasket material being performed during relative rotation between the can end and the applying means.

In testimony whereof I have signed my name to this specification in the presence 95 of two subscribing witnesses.

IVAN D. THORNBURGH.
